UNITED STATES PATENT OFFICE.

OSCAR H. PIEPER AND ALPHONSE F. PIEPER, OF ROCHESTER, NEW YORK.

SUPPORT FOR VALVE-HOUSINGS.

1,230,214.

Specification of Letters Patent. Patented June 19, 1917.

Application filed October 30, 1915. Serial No. 58,941.

To all whom it may concern:

Be it known that we, OSCAR H. PIEPER and ALPHONSE F. PIEPER, both of Rochester, in the county of Monroe and State of New York, have invented certain new and useful Improvements in Supports for Valve-Housings; and we do hereby declare the following to be a full, clear, and exact description of the same, reference being had to the accompanying drawings, forming a part of this specification, and to the reference-numerals marked thereon.

The present invention has to do with supports or mountings for valve housings and the like, adapted for maintaining a controlling valve for a fluid line, such as used for instance in connection with dental surgical apparatus, against a wall or other foundation, and the primary object of the structure constituting the present improvement resides in so designing and arranging the parts as to hold a housing or other member rigidly, and to effectively obviate its slightest movement. A further purpose of the invention is to afford an extremely simple and comparatively inexpensive construction, characterized by its efficiency as to strength, and further by the readiness with which it can be operatively applied to a housing or similar portion. To these and other ends the invention consists in certain improvements and combinations of parts, all as will be herein-after more fully described, the novel features being pointed out in the claims at the end of the specification.

In the drawings:

Figure 1 is a plan view showing the application of a preferred embodiment of the invention to a valve housing;

Fig. 2 is a side elevation;

Fig. 3 is a sectional view taken on the line 3^a—3^a of Fig. 2, and

Fig. 4 is a sectional view taken on line 4^a—4^a of Fig. 1.

Similar reference numerals in the several figures indicate the same parts.

In the structure shown, the supporting means embodies a pedestal 1 having a hollow portion 2 provided with a base flange 3 by which it can be attached to a wall or other support upon which the valve housing is to be mounted. Surmounting the hollow portion 2 is a base portion 4 and an offset portion 5 which is connected with the base portion by a curved surface 6 for a purpose that will appear more clearly presently. The base

and offset portions 4 and 5 are both provided with openings to receive screws 7 which pass therethrough and engage the valve housing 8. Within the latter is arranged a needle valve 9 controlled by the handle 10 and operable to open or close the port 11.

In the valve shown, which instances a type commonly employed for controlling air lines in connection with dental apparatus, the housing 8 is cylindrical, and the surface 6 is curved to conform to the periphery of the housing, which it engages throughout about a fourth of its entire surface, thereby affording a socket into which the housing 70 can be snugly fitted. The attaching screws 7 engage the housing at independent points arranged at intervals lengthwise of the supporting surface 6, and disposed at approximately an angle of forty-five degrees from each other with reference to the housing. As a result of this arrangement, the attaching devices act in conjunction with each other, to bind the housing by tension exerted along lines which are angularly disposed 75 with relation to one another, resulting in locking the housing in a most rigid and secure manner.

The structure that has been described is a most simple one, which can be manufactured 85 at a low cost while having the important advantages of permitting ready application of a housing and insuring its being held in absolutely fixed relation.

We claim as our invention:

1. The combination with a cylindrical valve housing, of supporting means therefor comprising a base portion and an offset portion projecting beyond the base portion and connected therewith by a curved surface 95 for engaging the housing, and securing devices adapted to pass through the base and offset portions for engaging the housing at independent points.

2. The combination with a cylindrical 100 valve housing, of supporting means therefor comprising a base portion and an offset portion projecting beyond the base portion and connected therewith by a curved surface for engaging the housing, and screws passing 105 through the base and offset portions and arranged substantially at right angles to each other for engaging the housing at independent points.

3. The combination with a cylindrical 110 valve housing, of supporting means therefor comprising a pedestal having a hollow por-

tion surmounted by a base and offset portion projecting beyond the base, and connected therewith by a curved surface for engaging the housing, the base having an opening communicating with said hollow portion through which a screw may be inserted into the opening to engage the housing, and the offset portion also having an opening to

receive a screw for engaging the housing in spaced and angular relation to the first mentioned screw.

OSCAR H. PIEPER.
ALPHONSE F. PIEPER.
